VENDING MACHINE

John H. McCormick and Frank M. Bender, Williamsport, Pa., assignors to Vend Cater, Inc., Williamsport, Pa., a corporation of Pennsylvania

Application September 27, 1930
Serial No. 484,835

2 Claims. (Cl. 194—63)

This invention relates to vending machines and more particularly to machines for vending bottled beverages. This application is a continuation in part of applicants' co-pending application, Serial No. 374,674, filed June 29, 1929, where-in there is disclosed in detail a machine of this type.

An object of this invention is an improved, reliable and efficient coin controlled means for preventing operation of the merchandise delivery mechanism except upon presentation to the vending machine of the proper coin or coins.

Other objects, novel features and advantages of the invention will be apparent from the following specification and accompanying drawings, wherein:

Fig. 1 shows a vertical section through one embodiment of the invention.

Fig. 2 is an elevation with the cover and parts carried thereby removed;

Fig. 3 is an elevation of the cover and parts carried thereby.

Fig. 4 is a partial view similar to Fig. 3 with the elements in different position;

Fig. 5 is a perspective view of a detail;

Figs. 6, 7 and 8 are sections on the lines 6—6, 7—7 and 8—8 respectively of Fig. 1.

Fig. 9 is a section on the line 9—9 of Fig. 10.

Fig. 10 is a section on the line 10—10 of Fig. 9.

Fig. 11 is a fragmentary view similar to Fig. 9 with the elements in a different position, and

Fig. 12 is a section on the line 12—12 of Fig. 9.

Referring now more especially to Figs 1 to 5 inclusive, 1 designates a rotatable drum constituting means for feeding bottles into position to be taken out from the machine by a purchaser. Rotation of the drum 1 is effected by means of a pinion 2 carried by a shaft 3 which projects through the wall of the container within which the drum 1 is mounted. The shaft 3 extends into a casing 4, having a cover 4^a. To the end of the shaft 3 there is fixed a collar 5, having a pair of segmental projections 5^a and a pair of peripheral shoulders 5^b. A shaft 6 is rotatably mounted in a bearing fastened to the cover 4^a and is provided at its inner end with a collar 7 having projecting tongues 7^a which project between the ends of the projections 5^a, thereby forming a lost motion connection between the shafts 6 and 3.

A collar 8 is keyed to the shaft 6 and has formed in one face coin grooves 8^a which a face plate 8^b overlies to hold coins therein. A ratchet plate 10 provided with teeth 10^a is carried by a hub of the collar 8 and a pawl 11 is provided to engage the teeth 10^a to prevent rearward rotation there-

of. The ratchet plate 10 is cut away on its periphery to provide a pair of shoulders 10^c adjacent the mouths of the coin slots and a lever 9 having a lug 9^a adapted to engage said shoulders is pivoted at 9^b. A spring 12 having its ends connected to the lever 9 and the pawl 11 tends to maintain both of these members in the position shown in Fig. 3.

A disk 13 is mounted on the hub of the member 8 and is provided with a pair of recesses 13^b having sloping sides. A lever 14 is pivoted at 14^a and is provided with a pin 14^b which is adapted to be received in either of the recesses 13^b. A spring 15 pulls the lever 14 in a direction to seat the pin in the recess.

The lever 9 is provided with a projection 9^c which is engageable by a coin in a coin slot to lift the lever, thereby moving the lug 9^a out of the path of the shoulders. A pawl 17 is provided to engage the shoulders 5^b to prevent forward rotation of the shaft 3. This pawl has an arm 17^a which is engaged by an extension 9^d from the projection 9^c. This pawl is lifted by the lever 9 to free the shaft 3.

In the upper part of the casing 4 there is provided coin chute 18 and selector for delivering coins to the coin slot 8^a. This selector is provided with coin testing means to prevent use of slugs to operate the machine. In the bottom of the casing there is provided a chute 19 to receive coins which have been used to effect operation of the device.

The coin slots 8^a are shown here as being deep enough to receive two coins, such, for example, as two nickels with the upper coin projecting slightly beyond the periphery of the collar 8. When the machine is at rest the collar 8 is arranged with one coin slot directly below the end of the coin chute and is maintained in this position by means of the lever 14 which tends to oppose rotation of the disk. The projection 9^a lies in the path of the shoulders 10^b and will permit only limited forward rotation. The pawl 11 engages a tooth 10^a to prevent rearward rotation. Should the knob 6^a be turned without inserting a nickel or after the insertion of only one nickel, the extent of rotation would be limited by the engagement of the lug 9^a with the shoulder. As soon as the knob was released it would be returned to normal position by the lever 14. After two coins have been inserted in the coin slot, rotation of the shaft 6 will bring the upper nickel into engagement with the projection 9^c of the lever 9 to lift the same, thereby moving the lug 9^a out of the path of the shoulder 10^b. The 110

pawl 17 will also be raised, thereby allowing rotation of the shaft 3. After the nickel has passed out of engagement with the projection 9^c, the pawl 9 will be returned to operative position and the lug 9^a will be engaged by the next shoulder, thereby preventing further rotation of the shaft. The shaft 3 will turn the drum 1 to effect delivery of a single article of merchandise and rotation of the shaft 3 will be stopped after a half 10 revolution by the pawl 17. The coins will drop out of the slot into the chute 19. The lever 14 will thereupon move the collar 8 rearwardly to locate the coin slot 8^a in alignment with the chute 18. The pawl 17 prevents over rotation of the 15 shaft 3 and prevents backlash on the shaft 6. The arrangement of the projections 5^a and tongues 7^a is such that they do not come into engagement until both the levers 9 and 17 have been lifted and the lost motion thereby provided is sufficient to 20 permit the above described operation of the shaft 6 when insufficient coins have been presented to the machine without affecting the position of the drum 1.

Referring now to the modification disclosed in 25 Figs. 9 to 12, a shaft 23 is journaled in the cover 25 of the housing 24, and its inner end is provided with a key to extend into a keyway provided in the end of the shaft 3 for connecting said shafts together. A handle 26 is connected to the outer 30 end of the shaft 23 and a collar 27 is connected to the inner end thereof. Integral with this collar is a disk 28 provided with a plurality of peripheral slots 29 and a like number of spaced groups of ratchet teeth. A bell crank lever 30 is pivoted to the housing 24 and the arm 30^a is adapted to engage the ratchet teeth to prevent rotation of the disk 28 in one direction. A lever 31 is pivoted to one wall of the housing 4 and is arranged to engage lugs 32 on the disk 28 to 40 prevent rotation of the disk in the other direction. The lever 31 is provided with an arm 33 which is adapted to be engaged by a coin located in a slot 29 to lift the lever 31 against the action of its spring 34 to a sufficient extent to move it out 45 of the path of the lugs 32. A blank space is left between the groups of ratchet teeth and the lugs 32 are so arranged that sufficient movement of the disk is permitted to engage a coin in slot 29 with the arm 33 before locking the disk against 50 reverse movement.

A coin chute 35 is provided for directing the coin into a slot 29 and guides 36 are provided for receiving coins dropped from the disk 28 and directing the same in back of a magnifying glass 37. A pivoted detent 38 has a horizontal flange which projects under the ends of the guide members 36 to hold a coin in position in back of the magnifying glass 37. A spring 39 tends to hold the detent 38 in operative position and pivoted 60 arms 40 are provided on the collar 27 to engage the upper end of the detent to trip the same, thereby allowing the coin to drop into the coin box 41. The arms 40 have projecting portions which engage the collar 27 to prevent rotation thereof 65 in one direction and are provided with light springs 40^a to resist yielding in the other direction.

In the operation of the above-described mechanism, a coin, preferably a dime, is dropped into 70 the coin chute 35 which directs it into a slot 29.

The customer now turns the handle 26, thereby bringing the coin into engagement with the arm 33 to lift the lever 31 out of the path of the lug 32 corresponding to the slot containing the coin. The coin holds up the lever 31 until the lug 32 underlies the lever 31. When the lugs 32 underlie the lever 31, the pawl 30^a engages the ratchet teeth of a group to prevent rearward rotation of the shaft 23. This shaft may now be rotated forwardly until the next lug 32 engages the lever 31 which will have been released by the first lug and returned to engaging position by its spring 34. Rotation of the shaft 3 is effective to move the drum 1 to effect delivery of one article of merchandise. The coin is dropped to the guides 36 and caught by the detent 38 which holds it suspended in front of the magnifying glass. On the next operation of the machine, this coin will be released, due to the fact that the detent 38 is tripped by an arm 40 at each operation of the machine.

The arm 30^b of the bell crank lever 30 is connected by a link 42 with an arm 43 connected to the rotating part of a lock 44. The lever 31 is likewise connected to the link 42. Thus when 100 the lock is operated by a key, the pawl arm 30^a is disengaged from the ratchet teeth and the lever 31 is lifted out of the path of the lug, thereby permitting free rotation of the shaft 23 in either direction. This mechanism is provided 105 to permit rearward rotation of the drum, if desired.

It is of course understood that various modifications may be made in the device above described, without in any way departing from the 110 spirit of the invention as defined in the appended claims.

We claim:

1. In a vending machine, a rotatable shaft, a collar carried by said shaft and having coin slots, 115 shoulders formed on said collar, a lever adapted to project into the path of said shoulders to limit rotation of said shaft in one direction, a second shaft having a lost motion connection with said first shaft, a lever engaging said second shaft to 120 limit rotation thereof in one direction, both of said levers being movable by a coin to inoperative positions, a disk carried by said collar and having peripheral recesses, a pivoted lever having a pin adapted to be received in said recesses, 125 and resilient means drawing said lever toward said disk.

2. In a vending machine, a rotatable shaft, a collar carried by said shaft and having coin slots, shoulders formed on said collar, a lever adapted 130 to project into the path of said shoulders to limit rotation of said shaft in one direction, a second shaft having a lost motion connection in the first shaft, a lever engaging said second shaft to limit rotation thereof in said direction, both of 135 said levers being movable by a coin to inoperative position, means to prevent rotation of said first shaft in the opposite direction, a disk carried by said collar and having a peripheral recess, a pivoted lever having a pin adapted to be 140 received in said recess, and resilient means drawing said lever toward said disk.

JOHN H. McCORMICK.
FRANK M. BENDER.
